MOTOR VEHICLE KEY

Robert M. Brosius, Chicago, Ill.

Application July 2, 1953, Serial No. 25,764

Term of patent 14 years

(Cl. D50—4)

To all whom it may concern:

Be it known that I, Robert M. Brosius, a citizen of the United States, residing in the city of Chicago, county of Cook, and State of Illinois, have invented a new, original, and ornamental Design for a Motor Vehicle Key, of which the following is a specification, reference being had to the accompanying drawings forming a part thereof.

Fig. 1 is a side elevational view of one side of a motor vehicle key showing my new design;

Fig. 2 is a side elevational view of the other side thereof;

Fig. 3 is a vertical sectional view taken upon line 3—3 of Fig. 1; and

Fig. 4 is a section taken upon the line 4—4 of Fig. 1. The dominant feature of my design resides in the motor vehicle key portion shown in full lines.

I claim:

The ornamental design for a motor vehicle key, as shown and described.
